DETECTION OF TOXIC GASES

William F. Fagen, Chicago, Ill., assignor to
 Stewart-Warner Corporation, Chicago, Ill., a
 corporation of Virginia

Application March 6, 1943, Serial No. 478,323

17 Claims. (Cl. 250—41.5)

1

The present invention relates to improvements in the detection of toxic gases and particularly to improved apparatus of the type including bridge circuit arrangements comprising photosensitive devices.

In the contemporaneously filed application of Willard H. Farr, myself, and Stanley Kolanowski, Serial No. 478,324, March 6, 1943, there is disclosed and claimed apparatus for detecting toxic gases, particularly carbon monoxide. The apparatus disclosed includes a differential bridge circuit having in it a pair of photosensitive devices. The bridge is energized from a battery and the control circuit associated with the bridge, which includes an electron tube, is energized from a low voltage source, such as the 24 volt source ordinarily found in airplanes for which the apparatus was particularly designed.

The present invention has for its primary object the provision of a new and improved control circuit whereby the apparatus may be energized from a single low voltage supply source, thereby eliminating the use of batteries or other ancillary power supply circuits.

A further object of the present invention is the provision of new and improved photosensitive gas detection apparatus operable from a single low voltage supply source and having means for compensating for like variations in the amount of light striking the photoelectric devices.

Another object of the present invention is to provide an improved differential photosensitive circuit arrangement including electronic tubes controlled by the photosensitive devices, wherein an indication is given of inoperative conditions of the electronic tubes, for instance, when one or the other of the tubes is "burned out."

Other objects and advantages of the present invention will become apparent from the ensuing description, in the course of which reference is had to the accompanying drawings, in which

Fig. 1 is a diagrammatic representation of one embodiment of the invention; and

Fig. 2 is a view similar to Fig. 1, of a second embodiment of the invention.

Before proceeding with a detailed description of the present invention, it may be well briefly to consider the primary use of the circuit arrangement of the present invention, which, as indicated above, is the detection of carbon monoxide, and particularly small quantities in short time intervals. In the detection of carbon monoxide a pair of photosensitive devices are utilized. These are connected in a bridge circuit and supplied with light from a single light source, preferably located between the devices. Associated with the devices is a substance having an photo-characteristic—preferably the light transmission characteristic—that changes in the presence of carbon monoxide. This substance is preferably

2

placed in glass tubes, each of which is located between the light source and an associated one of the photosensitive devices. Fresh air is passed through one of the tubes, which tube acts as a standard, while the air to be tested for the presence of carbon monoxide is passed through the second tube. The photosensitive devices are preferably connected in a differential balanced bridge circuit so that any unbalance of the bridge, as a result of the change in color transmitting characteristics of the substance in the tube through which the air to be tested is passed, is utilized to control electron tubes controlling some device such as a warning light, or the like.

15 The present apparatus is intended, primarily, for the detection of carbon monoxide within the cabins of airplanes that are heated by exhaust gases from the airplane engines. The fresh air passed through one of the tubes referred to above is preferably either fresh air from outside the cabin, or the fresh air in the cold air duct leading to the heat exchanger. The air to be tested is the heated air taken either from the inside of the cabin or from the hot air duct through which the heated air is supplied to the interior of the cabin.

20 Referring now to Fig. 1, the photoelectric tubes, which may be of the 923 type, are indicated by reference characters 10 and 12. These are located a short distance apart and between them is a light source, such as the lamp 14, which is continuously energized when the apparatus is in operation. The lamp is mounted within a housing 16, which also houses a pair of glass tubes 18 and 20 which contain a substance the color of which changes in the presence of carbon monoxide from a yellow progressively to a dark, blue-green. This photo-characteristic change is accompanied, among other things, in the change in the amount of light transmitted therethrough and this change is utilized in the apparatus to actuate a relay or the like. The carbon monoxide sensitive substance is described in the aforementioned contemporaneously filed application and the applications referred to therein.

25 The air to be tested, in this case the heated air, is supplied to glass tube 18 through a conduit 22 and the fresh air is supplied to the tube 20 through a conduit 24. It is preferred that the air passing through the tubes, that is, both the heated and fresh air, be at approximately the same temperature and that the velocity be relatively low. The apparatus for bringing them to the same temperature, restricting the flow, and the physical construction of the detection apparatus are more fully disclosed and also claimed in the previously referred to application Serial No. 478,324.

30 The photoelectric tubes are similarly connected

across a pair of low voltage supply lines 26 and 28, which may have a potential difference of 24 volts, the voltage usually used in airplanes. Photoelectric tube 10 is connected across the supply lines through a resistor 30, the tube being connected to the positive line 26 and the resistor to the negative line 28. The photoelectric tube 12 is similarly connected across the supply lines through an adjustable resistor 32. The resistor 30 may have a resistance of about three megohms and the resistor 32 a resistance of about five megohms.

The photoelectric tubes are utilized to control a pair of electron tubes 34 and 36 of the tetrode type (such, for instance, as the type 25B6G) and these tubes in turn control the operation of a differential relay 38. The relay has opposed windings 40 and 42 in the plate circuits of tubes 34 and 36, respectively, and a holding coil 44, which is effective under balanced conditions to maintain in closed position the relay operated switch 46. Switch 46 is either gravity or spring biased into open position.

The control grids 48 and 50 of electron tubes 34 and 36, respectively, are connected to the junctions of tube 12 and resistor 32 and of tube 10 and resistor 30 through conductors 52 and 54, respectively. The arrangement is such therefore that, as the amount of light impinging upon the two tubes is varied, the grid potentials of the tubes change to vary the flow of current through the differential windings 40 and 42 of the relay.

In order to compensate for like variations in the amount of light transmitted to the photoelectric tubes and thus to compensate for aging of the carbon monoxide responsive substance or the like, the grid connections are identically connected to their respective photoelectric tube circuits. In the instant embodiment the arrangement is such that when less light falls upon the photoelectric tubes, the grids become more negative as a result of the decreased flow of current through the resistors 30 and 32. Under ordinary or normal conditions the grids of the electron tubes are maintained at equal potentials so that the differential windings 40 and 42 are energized equally. This condition may be attained by adjustment of resistor 32 in circuit with photoelectric tube 12. When, however, carbon monoxide is present in the heated air stream passing through tube 18, less light falls upon photoelectric tube 10 than upon tube 12, with the result that the grid 50 of tube 36 becomes more negative than the grid 48 of tube 34, and the tube 36 thus passes less current than tube 34. Winding 42 of the differential relay is thus less effective than winding 40 and, at some current value determined by a sensitivity adjustment to be described hereinafter, the unbalance results in the opening of switch 46. It may be seen, therefore, that the winding 42 is so arranged as to tend to hold the switch closed, as is the holding winding 44. The winding 40, on the other hand, tends to open the switch.

Relay winding 40 is connected to the anode 56 of the tube 34 by a conductor 57 and to the positive supply line by a conductor 58. In similar manner relay winding 42 is connected to the anode 60 of tube 36 by conductor 62 and to the positive line 26 by the conductor 58.

The relay operated switch 46 is held in closed position under balanced current conditions by the winding 44, one terminal of which is connected to the power supply line by conductor 64 and the other to the negative supply line 28 by a con-

ductor 66, the cathode heater 68 of tube 34, and a conductor 70.

The electron tube and relay arrangement is such that the switch 46 opens in the event either of the tubes burns out. This is accomplished by connecting the relay winding 44 in series with the cathode heater 68 of tube 34 and by making the holding winding 44 stronger than either of windings 40 and 42 and just strong enough to hold the switch 46 in its operated or closed position under balanced conditions. Thus, under balanced conditions the switch is held closed by winding 44 but, should the tube 34 burn out, windings 44 and 40 will become ineffective, leaving effective only winding 42. This winding, however, is not strong enough to hold the switch 46 in its closed position so that when tube 34 burns out, the switch 46 is returned to its open position. In the event tube 36 should burn out, then winding 42 becomes ineffective, leaving the opposing windings 40 and 44 in circuit. The resultant effect is too small to hold the switch closed.

The cathode heater 72 of tube 36 is connected directly across the power supply lines by conductor 74 and the previously mentioned conductor 70.

The sensitivity of the apparatus is controlled by varying the portion of grid bias resistor 76 in the cathode circuits of the electron tubes. This is done by an adjustable resistor contact 78 connected by a conductor 80 to the cathodes 82 and 84 of tubes 34 and 36, respectively. To insure sufficient grid bias even when the current flow through the tubes is small, the bias resistor 76 is connected to positive power supply line 26 through a bleeder resistor 86. The other terminal of the bias resistor 76 is connected to the negative power supply line 28 by conductor 88.

Resetting of the relay after operation is accomplished by rebalancing the photoelectric tube circuits and momentarily closing a normally open push button switch 90 in circuit with relay winding 42. The switch is connected across conductors 62 and 28 through a current limiting resistor 92. This arrangement enables the relay winding 42 readily to be energized to an extent sufficient to move the switch 46 to its closed position.

The relay operated switch 46 may be utilized to control a signal lamp or to operate some device controlling either the supply of air to the airplane cabin or the operation of the heater. The control can be effected through the circuit 94 in which the switch 46 is located. When the switch is closed, the circuit 94 is also closed and when the switch is open, the circuit is opened.

In operation, the power supply lines 26 and 28 are connected to a low voltage source. The flow of current through the tubes and through the differential windings 40 and 42 is adjusted by adjustment of resistor 32 until the current flow is equal. As a result, the windings exert equal and opposing forces upon the switch 46 whereas the holding winding 44, which is supplied with the same current during normal operation, tends to hold the switch 46 in its closed position. To close switch 46 initially, it is necessary only momentarily to close switch 90, whereupon winding 42 is excessively energized and assists winding 44 to close the switch. Thereafter, the switch is maintained in its closed position by winding 44.

As long as there is no carbon monoxide in the heated air flowing through tube 18 and the light

transmitting characteristics of the sensitive gel in the tubes 18 and 20 remain the same or vary equally as a result of aging, or the like, the potentials applied to the grids of tubes 34 and 36 remain alike—that is, a balanced condition obtains. However, should the heat exchanger be punctured as by a bullet or otherwise develop a leak so that carbon monoxide from the exhaust gases is introduced into the heated air stream, then the carbon monoxide changes the sensitive gel from its original yellow color progressively to a dark blue-green color. Less light, therefore, passes to photoelectric tube 10 and the grid 58 of tube 36 becomes more negative, as heretofore explained. Less current flows through tube 36 and through relay winding 42, until the current reaches some low value at which winding 40 overcomes the joint effect of windings 42 and 44 and switch 46 opens. When the switch opens, the control circuit 94 is likewise opened for the purpose of (1) indicating the presence of the carbon monoxide, (2) operating some device controlling the operation of the heat exchanger or the supply of heated air to the cabin, or (3) both indicating and operating some device. The value of current at which the relay opens is determined by the sensitivity adjustment consisting of the adjustable contact 78 and the grid bias resistor 76, which, as explained heretofore, changes the grid bias applied to both tubes.

Once the relay has been operated then, for the apparatus again to be operated to detect and signal the presence of carbon monoxide, a new tube 18 of sensitive gel may be used or the resistor 32 may be adjusted to rebalance the circuit. The latter operation, of course, can be carried on only if the sensitive gel has not reached a darkened color such that it is no longer sufficiently sensitive to the presence of carbon monoxide. However, if it has not become too insensitive, then the circuit may be rebalanced by adjustment of resistor 32 and the switch 88 again momentarily closed to reset the relay. Thereafter, if carbon monoxide is again detected, the apparatus operates in the manner described above to release the relay.

It is advantageous to connect the photoelectric tubes 10 and 12 to the positive power supply line and the resistors to the negative power supply conductor. The reason for this is that the tubes are operated at a higher potential, and, when less light impinges upon them, their cathodes become more negative as do the grids of the electron tubes, which are connected to the cathodes. Thus, if the light source 74 associated with the photoelectric tubes should burn out, the grids become most negative and reduce the flow of current through the tubes. If the circuit was arranged to make the grids more positive when less light impinged on the photoelectric tubes, then, in the event the lamp burned out, the flow of current through the tubes would be increased. This latter result is not at all desirable.

A somewhat different circuit arrangement is illustrated in the embodiment of Fig. 2. Here a single winding relay is used and the flow of current through it is controlled by a pair of electron tubes. These are so arranged that when carbon monoxide is present the total flow of current through the winding is reduced to release the relay. Compensation for like variations in the sensitive substance, as by darkening resulting from aging, is provided by arranging the tubes so that the flow of current through one tube decreases and that through the other in-

creases, the total flow remaining substantially constant.

Referring now to Fig. 2 the photoelectric tubes 100 and 102 are connected across the power supply lines 26 and 28 through the adjustable resistors 104 and 106, respectively. The tube 100 is connected to the positive terminal, whereas the tube 102 is connected to the negative terminal, so that when less light impinges upon the tubes, the more negative becomes the cathode of the tube 100, whereas the anode of tube 102 becomes more positive.

In the embodiment of Fig. 2 the effective tube is tube 100, i. e., it is the tube associated with the heated air supply which is likely to become contaminated with carbon monoxide.

The electron tubes controlled by the photoelectric tubes are indicated by the reference characters 108 and 110, respectively. The control grid 112 of the former is connected to the cathode of photoelectric tube 100 by a conductor 114 and the control grid 116 of the tube 110 is connected to the anode of photoelectric tube 102 by a conductor 118.

The anode circuits of the two electron tubes are connected in parallel and the current flowing through the two tubes flows through the relay winding 120. One terminal of the relay winding is connected to the positive power supply line 26 by conductor 122 and the other terminal is connected to the anode 124 of tube 108 by conductors 126 and 128. This other terminal is also connected to the anode 130 of tube 110 by conductors 132 and 134. The cathode heaters 134 of the two tubes are connected in parallel and across the power supply lines by conductors 136 and 138. The cathodes 140 and 142 of the two tubes are joined together and connected by a conductor 144 to an adjustable contact 146 which serves to control the portion of a grid bias resistor 148 in the cathode circuit. One terminal of the bias resistor is connected to the negative supply line 28 by a conductor 150 and the other terminal is connected to the positive line 26 through bleeder resistor 152.

The relay operates a switch 154 which is normally closed, i. e., when the apparatus is in operation and in balance. The switch controls a circuit 156 controlling a signal lamp or some device for controlling the heated air to the cabin, or the like.

After the apparatus has once operated, it may be reset after balanced conditions obtain by momentary closure of a manually operable resetting switch 158, which energizes winding 120 through a current limiting resistor 160.

When the apparatus is initially placed in operation, the resistors 104 and 106 in circuit with the photoelectric cells are adjusted until the tubes 100 and 110 pass approximately the same current. The sensitivity control 146 is then adjusted to some point at which the total current flowing through the two tubes and through winding 120 is sufficient to maintain the switch 154 closed upon the momentary closure of the resetting switch 158.

When no carbon monoxide is present in the air, then the balanced condition described above obtains and the relay remains in its operated position. In the event the sensitive gel in the tubes 18 and 20 (which have been omitted from Fig. 2) darkens as a result of aging or the like, then the photoelectric tubes 100 and 102 become less conductive. The grid 112 of electron tube 100 is rendered more negative, whereas the grid 116

of electron tube 110 becomes more positive and flow of current through tube 108 is decreased, whereas the flow of current through tube 110 is increased. The changes in flow of current through the two tubes approximately balance so that there is but little variation in current flow through the relay winding 120 and the switch 154 remains in its operated position.

When carbon monoxide is present in the heated air, then photoelectric tube 108 is illuminated less than tube 102 and the flow of current through electron tube 108 is decreased. This decrease in current flow through the tube results in a decrease in current flow through the relay winding and, at some current value dependent upon the sensitivity adjustment, the switch 154 is opened. The switch 154 may, like the previously described switch 48, be biased into its open position by gravity or a spring.

After the device has operated as above indicated, it may be reset for operation, provided the color of the sensitive gel has not changed excessively, by readjusting the photoelectric cell circuits and momentarily closing the reset switch 158.

While the present invention has been described as being particularly adapted for use in connection with low voltage supply circuits, it should be understood that certain features thereof may be used in conjunction with higher voltage sources. In addition, the circuit arrangement may be advantageously utilized for the detection of substances or materials other than carbon monoxide, although it has proven to be extremely advantageous in the detection of carbon monoxide.

Having thus described my invention, what I claim as new and desire to secure by Letters Patent of the United States is:

1. In photosensitive detection apparatus, the combination including, a pair of photosensitive devices for providing two control voltages in response to the passage thereby of the substance to be detected, a pair of electron tubes of the type having control electrodes, said electrodes being supplied with said control voltages, a single relay controlled by both said tubes, and means associating said relay, tubes, and photosensitive devices so that said relay is normally in operated position and movable into non-operated position by dissimilar changes in light striking said photosensitive devices.

2. In photosensitive detection apparatus, the combination including, a pair of photosensitive devices for providing two control voltages, both of which become more negative as less light strikes the devices, a pair of normally conductive electron tubes of the type having control electrodes, said electrodes being supplied with said control voltages, and a differential relay normally held in operated position controlled by both said tubes, said relay including a pair of opposed windings each of which is in the anode circuit of one of said tubes.

3. In photosensitive detection apparatus, the combination including, a pair of photosensitive devices for providing two control voltages, both of which vary in the same manner in response to like changes in the amount of light striking the devices, a pair of electron tubes of the type having control electrodes, anodes, and cathodes, said electrodes being supplied with said control voltages, a source of anode potential for said tubes, a cathode resistor adjustably connected in circuit with the cathodes of both said tubes con-

nected across said source, and a differential relay controlled by both said tubes.

4. In photosensitive detection apparatus, the combination including, a pair of photosensitive devices for providing two control voltages, both of which vary in the same manner in response to like changes in the amount of light striking the devices, a pair of electron tubes of the type having control electrodes, said electrodes being supplied with said control voltages, a differential relay including opposed windings controlled by both said tubes and operable into one position upon a predetermined change in light striking the devices, a source of anode potential, said windings and tubes being connected across said source, and means including a switch for connecting one of said windings to said source independently of said tubes to operate said relay into another position.

5. In photosensitive detection apparatus, the combination including, a relatively low voltage supply source having positive and negative lines, a pair of photosensitive devices each connected across said lines through associated resistors, said resistors being connected to the negative line, a pair of electron tubes of the type having control electrodes, anodes, and cathodes, connections from each electrode to the junction of one of said devices and its associated resistor, a differential relay normally held in operated position controlled by both said tubes, said relay including a pair of opposed windings each of which is connected across the anode of one tube and the positive line, resistance means connected across said lines, and an adjustable connection from the cathodes of said tubes to said resistance means.

6. In photosensitive detection apparatus, the combination including, a pair of photosensitive devices for providing two control voltages, both of which vary in the same manner in response to like changes in the amount of light striking the devices, a pair of electron tubes of the type having control electrodes and cathode heaters, said electrodes being supplied with said control voltages, and means including a differential relay having a holding winding in series with the cathode heater of one tube for indicating operativeness of the apparatus.

7. In photosensitive detection apparatus, the combination including, a pair of photosensitive devices for providing two control voltages, both of which vary in the same manner in response to like changes in the amount of light striking the devices, a pair of electron tubes of the type having control electrodes and cathode heaters, said electrodes being supplied with said control voltages, and a relay controlled by both said tubes, said relay including a pair of opposed windings connected one in the anode circuit of each tube and a third winding aiding one of said pair of windings connected in series with the cathode heater of one tube for holding said relay in operated position under balanced current flow through said pair of windings.

8. In photosensitive detection apparatus, the combination including, a relatively low voltage supply source having positive and negative lines, a first and second photosensitive device connected across said lines, means for decreasing the light striking one of said devices in response to the presence of the material to be detected, resistors interposed between said devices and the negative lines, a first and second electron tube of the type having control electrodes, anodes, cathodes, and cathode heaters, connections from

the electrodes of said first and second tubes to the junctions of said first and second devices in their associated resistors, respectively, a relay normally held in operated position controlled by both said tubes, said relay including a pair of opposed windings, the first of which is connected across the anode of said first tube and the positive line, and the second of which is connected across the anode of said second tube and the positive line, said relay including also a third winding aiding the first and a switch movable into circuit closing direction by said first and third windings, said first two windings being unable to hold said switch closed and said third being unable to close it but able to hold it closed, and means connecting said third winding in series with the cathode heater of said second tube.

9. In photosensitive detection apparatus, the combination including, a pair of photosensitive devices for providing two control voltages varying in opposite senses in response to like changes in light striking said devices, a pair of electron tubes of the type having control electrodes, said electrodes being supplied with said control voltages, and a relay having a single winding connected in series in the anode circuits of both said tubes.

10. In photosensitive detection apparatus, the combination including, a pair of photosensitive devices for providing two control voltages one of which becomes more negative and the other more positive in response to less light striking said devices, a pair of electron tubes of the type having control electrodes, said electrodes being supplied with said control voltages and the anode circuits being connected in parallel, and a relay having a single winding in the parallel connected anode circuits of said tubes and normally closed switch means adapted to be opened when less light strikes said one of the devices than the other.

11. In photosensitive detection apparatus, the combination including, a pair of photosensitive devices for providing two control voltages varying in opposite senses in response to like changes in light striking said devices, a pair of electron tubes of the type having anodes, cathodes, and control electrodes, said electrodes being supplied with said control voltages and said anode-cathode circuits being connected in parallel, a cathode bias resistor in the cathode circuit of both said tubes, and a relay having a single winding in the parallel connected anode circuits of both said tubes.

12. In photosensitive detection apparatus, the combination including, a pair of photosensitive devices for providing two control voltages varying in opposite senses in response to like changes in light striking said devices, a pair of electron tubes of the type having control electrodes, said electrodes being supplied with said control voltages, a relay having a single winding in the anode circuits of both said tubes, and switch means for changing the current flow through said relay independently of said tubes.

13. In photosensitive detection apparatus, the combination, including, a relatively low voltage supply source having positive and negative lines, a pair of photosensitive devices each connected across said lines through associated resistors, one of said resistors being connected to the negative line and the other to the positive line, a pair of electron tubes of the type having control electrodes, anodes, and cathodes, connections from each electrode to the junction of one of said de-

vices and its associated resistor, a relay normally held in operated position controlled by both said tubes, said relay including a single winding connected across the anodes of both tubes and the positive line, resistance means connected across said lines, and an adjustable connection from the cathodes of both said tubes to said resistance means.

14. In photosensitive detection apparatus, the combination including, a control circuit including a pair of photosensitive devices, a pair of electron tubes controlled conjointly by said control circuit, a relay controlled by both said electron tubes, and a single low voltage direct current source of energy conductively connected to said devices and tubes.

15. In photosensitive detection apparatus, the combination including, a control circuit including a pair of photo-sensitive devices, a pair of electron tubes of the type having control electrodes, said electrodes being supplied with control voltages from said control circuit such as to render the tubes normally conductive, a single relay controlled in response to a change in the ratio of currents flowing through the tubes, and means associating said relay, tubes, and control circuit so that a change in current ratio occurs and said relay is operated by dissimilar changes in light striking said photosensitive devices.

20 16. In photosensitive detection apparatus, the combination including, a control circuit including a pair of photosensitive devices and a pair of normally conductive electron tubes controlled thereby, a relay normally energized and operated by the current flowing through said electron tubes, and signal means operated by said relay in its energized position, whereby said signal means is effective also to provide a signal of the inoperativeness of the apparatus.

25 17. In photosensitive detection apparatus, the combination including, a control circuit including a pair of photosensitive devices, a pair of electron tubes of the type having control electrodes, anodes and cathodes, said electrodes being supplied with control voltages from said control circuit, a source of potential, said anodes and photosensitive devices being connected to said source, a cathode resistor adjustably connected in circuit with the cathodes of both said tubes and connected across said source, and a relay controlled by both said tubes.

Certificate of Correction

Patent No. 2,425,059.

August 5, 1947.

WILLIAM F. FAGEN

It is hereby certified that error appears in the printed specification of the above numbered patent requiring correction as follows: Column 10, line 12, claim 14, strike out the word "conjointly" and insert the same after "controlled" in line 13, same claim; and that the said Letters Patent should be read with this correction therein that the same may conform to the record of the case in the Patent Office.

Signed and sealed this 14th day of October, A. D. 1947.
